PERFORATING MACHINE

Harrison P. Holbrook, Whitman, Mass.

Application September 3, 1932, Serial No. 631,680

4 Claims. (Cl. 164—93)

The present invention relates to perforating machines which are used in the manufacture of shoes to form ornamental cutouts and ventilating openings in shoe parts.

Generally, these perforating machines are provided with a bed, a presser member having a work-engaging face mounted for movement toward and away from the bed, and a die having upstanding cutting edges interposed between the bed and the presser member to pierce the shoe part placed between the die and the presser member. As first constructed the die was mounted to slide, like a drawer, on the bed into and out of position beneath the presser member. Later, in order to operate upon made shoe uppers closed by the back seam, it was considered advisable to support the die upon an elevated structure called an anvil, which was mounted to slide, clear of the lateral sides of the machine, into and out of position beneath the presser member. Many perforating machines provided with die supporting structures of the anvil type went into commercial use. For some time past, however, shoe manufacturers have preferred to employ dies of the original flat bed type in the perforating machines of the anvil type, and in consequence it has been necessary to provide the top of the anvil with a guideway to receive the dies of the flat bed type. But whether the dies are of the anvil or flat bed type, it is the general practice for commercial die makers to furnish the shoe manufacturers with the dies for use in the perforating machines. The die makers have a perforating machine in which they test the die before it is sent out to the shoe manufacturer. One important test is to determine whether the cutting edges of the die and the work-engaging face of the presser member are in parallel horizontal planes. If they are not located in such planes, the presser member will engage one portion of the shoe part before another, with the result that the cutting edges beneath the shoe part last engaged by the presser member will cut light. When this occurs, the die makers level the cutting edges of the die by planing the bottom surface thereof. But when the tested die is sent to the shoe manufacturer for insertion in the shoe factory perforating machine, it is found that owing to many conditions such as wear, maladjustment and foundation settling, the cutting edges of the die and the work-engaging face of the presser member are not in parallel horizontal planes, notwithstanding the careful workmanship of the die maker. While the die maker is blamed, the

usual remedy is for a shoe factory employee to shim the die in an attempt to locate the cutting edges in a horizontal plane parallel to the work-engaging face of the presser member.

The principal object of the present invention is to provide the perforating machine with means for relatively adjusting the die and the presser member to locate the work-engaging face thereof and the cutting edges of the die in parallel horizontal planes.

To the accomplishment of this object and such others as may appear hereinafter, the features of the present invention consist in certain devices, combinations, and arrangements of parts fully described hereinafter and then pointed out in the claims which possess advantages readily apparent to those skilled in the art.

The various features of the present invention will be readily understood from an inspection of the accompanying drawings illustrating the best form of the invention at present known to the inventor, in which

Figure 1 is a view in front elevation of a perforating machine;

Fig. 2 is a view in plan of the die and the supporting structure therefor;

Fig. 3 is a view in sectional elevation on the line 3—3, Fig. 2;

Fig. 4 is a view in sectional elevation on the line 4—4, Fig. 3, and

Fig. 5 is a detail view in left side elevation of the pivotal connection between the die support and the base member of the die supporting structure.

For purposes of disclosure the various features of the present invention are illustrated as being embodied in the perforating machine disclosed in the patent to Knight, No. 1,584,230, May 11, 1926. As shown, the machine (Fig. 1) is provided with a bed 6 and a presser member 7, having a work-engaging face 8, which is reciprocated towards and away from the bed 6 by connections from some suitable source of power. As is usual, the bed 6 is provided with a guide 9 medially located between opposite lateral edges thereof. Mounted to slide horizontally on the bed 6 is an anvil 10 provided on its bottom with a central groove 11 which receives the guide 9.

The top of the anvil 10 carries a grid 12 (Figs. 2 and 3) which forms a supporting surface for a die 13, of the flat bed type, mounted to slide on the grid into and out of position beneath the presser member 7. To this end the grid 12 is provided with the yoked arms 14, the lateral

edges 15 of which are formed to guide the die in its sliding movement.

As shown in Figs. 2 and 3, the die is provided with a plurality of tubes 16 having upstanding cutting edges 17 for forming a plurality of ventilating openings 18 in the vamp and lining of a shoe upper 19 closed by a back seam. The shoe upper 19 is supported on the die so that the parts to be perforated extend over the cutting edges 17, (Figs. 2 and 3).

In order to locate the work-engaging face 8 of the presser member 7 and the cutting edges 17 in parallel horizontal planes, the anvil 10 is formed in two parts, namely, a support 20 (Figs. 15 4 and 5) to which the grid 12 is secured, and a base member 21 which slides on the bed 6. The support 20 and the base member 21 are tied together in a manner permitting limited relative movement by a pair of vertical bolts 22 (Fig. 2) 20 the bottoms of which are threaded to receive nuts 23 (Fig. 3) which are mounted in countersinks formed in the bottom of the base member 21. The upper ends of the bolts 22 pass loosely into chambers 24 formed in the support 20. 25 Coiled about the shank of each bolt 22 and interposed between the head thereof and the chamber 24 is a spring 25.

Secured to the base member 21 is a horizontal bearing pin 26, the opposite ends of which 30 are journaled in ears 27 (Fig. 4) formed at the lower rear end edge corners of the support 20. In order to tip the support 20 on the pin 26, the bottom of the support, which is inclined upwardly and forwardly, is engaged by the inclined 35 face on a wedge 28, the flat face of which engages the flat top face of the base member 21.

To reciprocate the wedge 28 in engagement with the bottom of the support 20 and with the 40 top of the base member 21, the center of the bearing pin 26 is bored transversely to receive the reduced end of a spindle 29 which extends upwardly and forwardly in a slot 30 formed in the bottom of the support 20. The spindle 29 rotates in the pin 26 but is held from movement 45 longitudinally by a shoulder 31 and a collar 32 which embrace the pin 26. The spindle 29 may be rotated by a finger piece 33 secured to the forward end thereof. Intermediate its ends the spindle 29 is threaded to receive a nut 34 which 50 is secured in a recess 35 formed on the inclined face of the wedge 28. The wedge is guided in its reciprocating movement by the shanks of the bolts 22 which pass loosely through slots 36 formed through the wedge.

55 With the perforating machines in the shoe and die factories, respectively, provided with the various features of the present invention, the die maker is able to locate the work-engaging face of the presser member and the cutting edges of the die in parallel horizontal planes, knowing that when the die is sent to the shoe factory a simple manipulation of the finger piece 33 will enable the operative to locate the

work-engaging face and the cutting edges of the die in parallel horizontal planes notwithstanding variations in the shoe factory perforating machine from the die factory perforating machine.

The die supporting structure 10 is not weakened by being divided into the two parts 20 and 21 as the wedge engages their adjacent faces and constitutes an important element in transmitting without breakage the heavy pressure exerted by the presser member to the bed 6.

Nothing herein explained is to be interpreted as limiting the invention in the scope of its application to use in connection with the particular apparatus or the particular mode of operation or both selected for purposes of illustration and explanation. While the particulars of construction herein set forth are well suited to one mechanical form of the invention, it is not limited to these details of construction, nor to the conjoint use of all its features, nor is it to be understood that these particulars are essential since they may be modified within the skill of the artisan without departing from the true scope of the actual inventions, characterizing features of which are set forth in the following claims by the intentional use of generic terms and expressions inclusive of various modifications.

What is claimed as new, is:

1. In a die press, the combination with means for forming cut-outs in a shoe part and means for supporting the cut-out means for horizontal movement, of means for tipping the supporting means bodily about an axis extending transverse to the horizontal movement of the cut-out means.

2. In a die press, the combination with means for forming cut-outs in a shoe part, a support upon which the cut-out means slides, a base member to which the support is pivoted, of a wedge interposed between the support and the base member.

3. In a die press, the combination with means for forming cut-outs in a shoe part, a support upon which the cut-out means slides, a base member to which the support is pivoted, of a wedge interposed between the support and the base member, and means for adjusting the position of the wedge longitudinally to tip the support.

4. A die supporting structure having, in combination, means for forming cut-outs in a shoe part, a support therefor, a base member having a transverse bearing rod journaled in the support, a wedge interposed between the support and the base member, and means for adjusting the wedge longitudinally comprising a threaded spindle having one end rotatably mounted in the rod, a finger piece at the other end of the spindle to facilitate its rotation, and a nut, threaded to receive the spindle, secured to the base member.

HARRISON P. HOLBROOK.
